UNITED STATES PATENT OFFICE.

JERRY G. HUMPHREY, OF JACKSONVILLE, FLORIDA.

DEVICE FOR PROPELLING VESSELS.

1,315,505.

Specification of Letters Patent.

Patented Sept. 9, 1919.

Application filed March 29, 1918. Serial No. 225,563.

To all whom it may concern:

Be it known that I, JERRY G. HUMPHREY, a citizen of the United States, residing at Jacksonville, in the county of Duval and

5 State of Florida, have invented new and useful Improvements in Devices for Propelling Vessels, of which the following is a specification.

This invention relates to devices for propelling and for assisting in the propulsion of vessels and the invention is in the nature of a collapsible device which when forcibly projected in a rearward direction with respect to the vessel on which it is mounted 10 will expand and cause the vessel to be driven forwardly while, by its retractive movement, the device will be folded so as to present relatively small resistance to the progress of the vessel.

20 One object of the invention is to produce a simple and improved collapsible propulsion device of the character described.

A further object of the invention is to produce a simple and improved means for supporting the propulsion device and for actuating the same.

Further objects of the invention are to simplify and improve the construction and arrangement of the detailed parts entering 30 into the construction of the device.

With these and other ends in view which will readily appear as the nature of the invention is better understood, the same consists in the improved construction and novel 35 arrangement and combination of parts which will be hereinafter fully described and particularly pointed out in the claims.

In the accompanying drawings has been 40 illustrated a simple and preferred form of the invention; it being, however, understood that no limitation is necessarily made to the precise structural details therein exhibited, but that changes, alterations and modifications within the scope of the claims may be 45 resorted to when desired.

In the drawings:

Fig. 1 is a side elevation, partly in section, showing a portion of a vessel to which the invention has been applied.

50 Fig. 2 is a longitudinal sectional view of a part of the same.

Fig. 3 is a plan view of the collapsible propulsion device showing the same collapsed.

55 Fig. 4 is a plan view of the propulsion device showing the same partly extended.

Fig. 5 is a rear elevation of the propulsion device showing the same extended.

Corresponding parts in the several figures are denoted by like characters of reference. 60

The body 15 of the improved propulsion device consists of a flat rectangular plate with the side edges of which wings or doors 16 are connected by hinges 17. Secured on the rearward face of the plate 15 near the ends 65 thereof are rods or keepers 18, the same being disposed in longitudinal alinement with respect to each other. Swingingly mounted on each of the rods 18 is a yoke 19 the bridge portion of which is connected with one of the wings or doors 16 by means of a link 20, the yokes 19 being connected with the two oppositely disposed doors 16. Coiled about each of the rods 18 is a spring 21 having one terminal arm 22 that abuts on the face 70 of the plate 15 and another terminal arm 23 which is provided with a hook 24 engaging one of the limbs of the yoke 19. The springs 21 are so constructed and arranged that through the medium of the yokes 19 75 and links 20 they will serve to exert a closing action on the two doors, tending to swing said doors to the position shown in Fig. 3, approximately at right angles to the plate 15. 85

The plate 15 is provided with a centrally disposed socket 25 through which passes a rod 26 carrying a head 27 whereby movement of the plate and related parts in a rearward direction with respect to the rod 90 26 is obstructed. The head 27 is connected with the doors 16 by obliquely disposed links 28, the same being connected with the doors by means of staples 29 which are of sufficient dimensions to permit a certain degree 95 of lost motion when the device is in operation. A spiral spring 30 is arranged within the socket 25, one end of said spring bearing against the bottom of the socket and the other end against the head 27. 100

In Fig. 1 of the drawings there is shown a portion 31 of the hull of a vessel in which is arranged a steam cylinder 32 having a reciprocating piston rod 33 which is connected with the forward end of the rod 26 carrying the improved propulsion device, the joint 34 between the piston rod and the rod 26 being supported by a cross head 35 traveling on a guide way 36. The rod 26 is guided through a tubular casing 37 which 105 extends through the stern of the vessel, said casing being provided at the ends thereof 110

with stuffing boxes 38. The casing 37, the connection of which with the vessel should be perfectly water-tight, is equipped with a downwardly extending branch 39, the outlet 5 of which is closed by the spring actuated valve 40, best seen in Fig. 2. If, during the operation of the device, water should leak within the tubular casing 37, such water will be expelled through the valve branch or passage 39.

The vessel, a portion of which is seen in Fig. 1, has been shown as being equipped with a screw propeller 41 of ordinary construction, but no driving means for such 15 propeller are shown and claimed. A rudder post 42 carrying a rudder 43 is stepped at its lower end in a bearing 44 mounted on the tubular casing 37, thus affording a convenient and effective supporting means for 20 the rudder.

The doors or wings 16 have been shown as being provided on the rear faces thereof, and adjacent to their free edges, with reinforcing ribs or flanges 45.

25 The plate 15 is provided with a bracket 46 serving to support a ring or link 47. The wings or doors 16 are each provided with a bracket 48. The brackets 48 are connected with the ring or link 47 by 30 means of springs 49, said springs serving at the proper time to exert an opening on the wings or doors 16 in opposition to the closing action of the springs 21. Flexible elements, such as chains 50, are utilized 35 to connect the head 27 with the wings or doors 16, said chains serving to brace the device by limiting the opening movement of the wings or doors.

40 In the operation of this invention, when the rod 26 is thrust in a rearward direction by the action of the piston rod 33, such action will be assisted by expansive action of the spring 30. By the resistance of the water against which the device is projected, the 45 doors or wings 16 will swing open against the tension of the springs 21 until further opening of said doors or wings is prevented by the links 28, the latter serving to limit the opening movement of the doors. The doors together with the plate 15 will now 50 present a surface of large area against the resistance of the water whereby the vessel will be forcibly projected in a forward direction. By the retracting stroke the closing or 55 collapsing of the doors will be assisted by the springs 21 and at the limit of the retractive movement of the rod 26 with respect to the plate 15 the head 27 will engage the spring 30 which latter will now act as a buffer to 60 take up the shock. The doors being closed or collapsed by the retractive motion of the op-

erating rod, a surface of relatively restricted area will be presented to the resistance of the water which will not materially interfere with the progress of the vessel.

65

Having described the invention what I claim as new is:

1. In a propulsion device for vessels, a rod, means for reciprocating the same, a plate slidably connected with the rod, doors 70 hingedly connected with the plate, spring means for closing or collapsing the doors with respect to the plate and means connecting the doors with the rod for limiting the opening movement of the doors.

2. In a propulsion device for vessels, a rod, means for reciprocating the same, a plate having a socket through which the rod slidably extends, a head carried by the rod, a spring mounted in the socket and 80 abutting on the head, doors hingedly connected with the plate, spring means for collapsing the doors with respect to the plate, and links connecting the doors with the head carried by the reciprocatory rod for limiting 85 the opening movement of the doors.

3. In a device of the class described, a plate, rods carried by said plate in longitudinal alignment near the ends thereof, doors hingedly connected with the side edges of 90 the plate, yokes swingingly mounted on the rods, links connecting the yokes with the respective doors, springs coiled on the rods and actuating the yokes to close the doors, means for supporting and reciprocating the 95 plate, and means for limiting the opening movement of the doors.

4. In a device of the class described, a plate having doors hingedly connected therewith, a rod extending slidably through the 100 plate and having a head, spring means for closing or collapsing the doors, links connecting the opening movement thereof, a tubular casing through which the rod is slidably guided, said casing having a valved 105 outlet and said casing extending through the stern of a vessel, and means for effecting reciprocatory movement of the rod.

5. In a propulsion device for vessels, a rod, means for reciprocating the same, a 110 plate having a socket through which the rod slidably extends, a head carried by the rod, a spring mounted in the socket and abutting on the head, doors hingedly connected on the plate, spring means for collapsing 115 the doors with respect to the plate, and means including flexible elements such as chains connecting the doors with the head carried by the reciprocatory rod for limiting the opening movement of the doors.

In testimony whereof I affix my signature.
JERRY G. HUMPHREY.
